(57) **CLAIM**

The ornamental design for a bottle cap accessory, as shown and described.

DESCRIPTION

FIG. 1 is a top-front-left perspective view of a bottle cap accessory showing my new design;

FIG. 2 is a bottom-rear-right perspective view thereof;

FIG. 3 is an enlarged front elevational view thereof;

FIG. 4 is an enlarged rear elevational view thereof;

FIG. 5 is a top plan view thereof;

FIG. 6 is a bottom plan view thereof;

FIG. 7 is a right elevational view thereof;

FIG. 8 is a left elevational view thereof; and,

FIG. 9 is a perspective cross-sectional view taken along line 9-9 in FIG. 6.

The broken lines showing threading in FIGS. 2, 6, and 9 are included for the purpose of illustrating environmental structure and form no part of the claimed design.

In FIGS. 6 and 10, the dash-dot-dash broken line represents a sectional designation that forms no part of the claim.
